(57) **CLAIM**

The ornamental design for a combination tandem axle wheel chock and trailer tongue stand, as shown and described.

DESCRIPTION

This application is being filed contemporaneously with application for U.S. Letters Patent Ser. No. 10/710,514, entitled Combination Tandem Axle Wheel Chock and Trailer Tongue Stand, which is hereby incorporated by reference herein.

FIG. 1 is a perspective view of an combination tandem axle wheel chock and trailer tongue stand embodying our design; FIG. 2 is a plan view of the combination tandem axle wheel chock and trailer tongue stand depicted in FIG. 1;

FIG. 3 is a side elevation view of the combination tandem axle wheel chock and trailer tongue stand depicted in FIG. 1, with the opposite side elevation being a mirror image thereof;

FIG. 4 is an end elevation view of the combination tandem axle wheel chock and trailer tongue stand depicted in FIG. 1, with the opposite end elevation view being a mirror image thereof; and,

FIG. 5 is a bottom view of the combination tandem axle wheel chock and trailer tongue stand depicted in FIG. 1.
